UNITED STATES PATENT OFFICE.

JOHN A. MEROZ, OF WALTHAM, MASSACHUSETTS.

WATCH-ADJUSTING MEANS.

1,159,242.

Specification of Letters Patent.

Patented Nov. 2, 1915.

Application filed September 4, 1912. Serial No. 718,441.

To all whom it may concern:

Be it known that I, JOHN A. MEROZ, a citizen of Switzerland, and a resident of Waltham, in the county of Middlesex and

5 State of Massachusetts, have invented a new and Improved Watch-Adjusting Means, of which the following is a full, clear, and exact description.

The invention relates to horology, and its 10 object is to provide a new and improved watch-adjusting means, more especially designed for mechanically adjusting watches without removing the balance, and to insure accurate running of the watch whether the 15 latter is carried or held in a vertical or horizontal position.

For the purpose mentioned use is made of a roller ring carrying a roller table provided with a roller, the roller ring being adjustably secured to the balance wheel to permit 20 of turning the said roller ring without removing the balance from the watch. Use is also made of a hair-spring adjusting device consisting of a turnable regulator provided 25 with two graduations and a stud held on a ring mounted to turn, the ring having two pointers indicating on the said graduations to indicate the displacement of the hair spring and the displacement of the regulator 30 pins while making the adjustment.

A practical embodiment of the invention is represented in the accompanying drawings forming a part of this specification, in which similar characters of reference indicate 35 corresponding parts in all the views.

Figure 1 is an enlarged plan view of the watch balance provided with adjusting means; Fig. 2 is a sectional side elevation of the same on the line 2—2 of Fig. 1; Fig. 3 40 is an enlarged plan view of the roller ring; Fig. 4 is an enlarged sectional side elevation of the balance wheel; Fig. 5 is a similar view of the same with the roller ring shown partly detached; and Fig. 6 is an enlarged 45 plan view of the regulator and the adjusting means therefor.

It is well known that position adjustment of watch movements deals with the balance, the balance staff, the hair spring and collateral parts, such as the escapement, roller, fork, etc. Position adjustment aims to overcome the tendency of the watch movement to a change in rate when its position is changed and gravitation and friction are the 50 essential factors considered in position adjusting. With the improvements presently

to be described position adjustment is accomplished without requiring removal of the balance or other parts from the watch movement.

The staff A of the balance wheel B is journaled in the usual bearings C and C' carried by the balance cock D and the plate E, as plainly indicated in Fig. 2. The roller F is attached in the usual manner to the roller table F' secured centrally to a ring F² provided on its peripheral edge with an annular rabbet F³ engaged by the heads G' of screws G screwing in the diametrical arm B' of the balance wheel B. The head G' of each screw G is provided with a rabbet G² fitting the rabbet F³, and each screw G is provided at the head G' with a cross slot G³ and a similar slot G⁴ is at the terminal of each screw so that the latter can be turned from the top of the balance wheel to permit of loosening or fastening the corresponding screw G. When it is necessary to adjust for a correct beat of the escapement then the screws G are loosened so that the ring F² 60 can be turned to move the roller F into proper position relative to the fork of the pallet (not shown), and when the desired position is reached the screws G are screwed up to securely fasten the ring F² in position 65 on the cross arm B' of the balance wheel B. Thus by the arrangement described the roller F can be properly adjusted without removing the balance wheel from the watch movement. The ring F² is provided at its rim 70 with apertures F⁴ for engagement with a suitable tool in the hands of the operator for turning the ring F² whenever the screws G are loosened, as above described. The ring F² is also provided with a central dished hub F⁵ and an integral cross arm F⁶, and the hub F⁵ is secured to the roller table F'. A roller table F' is secured to the under side of the dished hub F⁵ to locate the roller F in the plane of the pallet. 75

From the foregoing it will be seen that the roller F can be readily adjusted for producing a correct beat without danger of injuring the hair spring or the balance wheel or disturbing the mounting of the balance 80 wheel.

It is noted that the screws G and the rim of the roller ring F² are located outside of the hair spring H and hence the latter is not liable to be touched when adjusting the roller ring. By making the roller ring detachable from the balance 85 90 95 100 105 110

wheel, the watchmaker, jeweler or repairer can readily replace a broken roller pin by a new one at the time the roller ring is detached from the balance wheel, so that the operator is not liable to bend the balance wheel arm or disturb the balance wheel pins or unduly heat the balance wheel or its staff when setting the roller pin in position with shellac. The balance wheel can be safely placed aside while replacing a roller pin by a new one on the roller table held on the detached roller ring.

The hair spring H is secured at its inner end to the collet I attached to the staff A, and the outer end of the hair spring H is secured in a stud J by the use of a set screw K or other means. The stud J is held in an arm J' projecting outwardly from a ring J² mounted to turn on an annular bearing D' rising from the top of the balance cock D, as indicated in Fig. 2. The ring J² is provided on top with a rabbet J³ engaged by a cape or retaining ring L fastened in place on the balance cock D by screws L' so that the ring J² is free to turn without danger of upward or downward displacement. It is understood that on turning the stud ring J² the stud J is shifted to cause the hair spring H to be adjusted to increase or decrease its tension.

The hair spring H passes between the regulator or curb pins N' of the regulator N, which latter is in the form of a sector having inwardly-extending radial arms terminating in a ring-shaped bearing N³ mounted to turn on the peripheral face of the ring J², as plainly indicated in Fig. 2, the ring N³ resting on top of the balance cock D. The regulator N is provided on its peripheral face with micrometric teeth N⁴ in mesh with a pinion O attached to a stud O' mounted to turn on the balance cock D, so that when the stud O' is turned a turning motion is given to the pinion and to the regulator N to shift the regulator pins N' nearer to or farther from the stud J according to the direction in which the stud O' and the pinion O are turned. The regulator N is provided with graduations N⁵ and N⁶, of which the graduation N⁵ and its pointer J⁴ serve to indicate displacement of the hair spring, while the graduation N⁶ and the pointer J⁵ serve to indicate displacement of the regulator pins N'. The graduations N⁵ and N⁶ are arranged in proportion to the teeth N⁴ of the regulator N, and the teeth of the pinion O to provide a micrometric adjustment, each degree of the graduation N⁶ being one one-hundredth part of a millimeter, and each degree of the graduation N⁵ being one-tenth part of a millimeter, that is, ten times more than a degree of the graduation N⁶.

Presuming that the regulator pins N' are in correct position, and it is necessary to ad-

just the hair spring H then the stud ring J² is turned and in doing so the stud is moved nearer to or farther from the regulator pins N' according to the direction in which the stud ring J² is turned.

The turning of the stud ring J² causes a shifting of the pointer J⁵ relative to the graduations N⁶ and is equivalent to the displacement of the stud J. In order to correct this defect, the number of degrees through which the pointer J⁵ has been shifted is noted by the operator, and after the hair spring is correctly adjusted the regulator is turned backward the same number of degrees, that is, until the pointer J⁵ again indicates on the same degree of the graduation N⁶ it had at the beginning. It will further be noticed that on adjusting the pins N' relative to the stud J the pointer J⁵ indicates on the graduation N⁶ the number of degrees moved for correction toward fast or slow. The pointer J⁴ indicates on the graduation N⁵ how many degrees the hair spring H is displaced in reading.

It will be seen that I arrange the unit graduations N⁵ along the arc of a circle and the fractional graduations N⁶ along another arc of the same circle, and that the ring J², which is movable relatively to said circle, has a pointer for the unit graduations and a separate pointer for the fractional graduations, so that I do not confuse the reading along the unit graduations by the readings along the fractional graduations or vice versa. By this means I facilitate the accurate reading of the graduations, which are necessarily very small in a watch, by avoiding confusion of one set of graduations with the other.

By reference to Fig. 2, it will be noticed that the pointers J⁴, J⁵ are flush with the upper faces of the regulator N and the cape or retaining ring L, and the terminals of the pointers J⁴, J⁵ are in close proximity to the inner surface of the sector-shaped regulator N. The cape or retaining ring L serves to fasten the stud ring J² in place and to maintain the regulator N in straight position on the balance cock D, and it also holds the top end stone C² of the head bearing C in position, as will be readily understood by reference to Fig. 2.

It is understood that by the arrangement described the roller ring can be turned on the balance wheel to adjust the roller relative to the fork of the pallet, and the hair spring H can be adjusted on turning the pinion O or the stud ring J² or both. It is further understood that when the stud ring J² is turned in one direction the roller F is liable to move out of beat, and in order to correct this defect the roller ring is turned on the balance wheel to move the roller into correct position relative to the fork of the pallet.

Having thus described my invention, I claim as new and desire to secure by Letters Patent:

1. In a watch, a staff, a balance cock, a ring mounted to turn on the cock and provided with an arm and two pointers, a hair spring having one end secured to the staff and its other end to the arm of said ring, a regulator mounted to turn on the said ring and provided with two graduations and with regulator pins, and means for turning the regulator.
2. In a watch, a balance cock having an annular bearing, a rabbeted ring mounted to turn on the said bearing and provided with an arm carrying a stud to which a hair spring is adapted to be secured, a retaining ring engaging the rabbet of the ring and secured to the balance cock, and a regulator mounted to turn on the peripheral face of the rabbeted ring below the retaining ring.
3. In combination with a balance cock

having a raised annular bearing, a stud, a ring mounted to turn on the said bearing and having an arm carrying the said stud, 25 the said ring having a rabbet at its inner edge and a radial pointer at its outer edge, a retaining ring, screws fastening the said retaining ring to the balance cock, a regulator sector having a graduation on which 30 indicates the said pointer, the terminal of the latter being adjacent to the inner edge of the sector, radial arms on the sector, and a hub on the arms and mounted to turn on the peripheral face of the stud carrying 35 ring below the cape or retaining ring.

In testimony whereof I have signed my name to this specification in the presence of two subscribing witnesses.

JOHN A. MEROZ.
